GARMENT

Alfred J. Marrow, University Place, N. Y., and Hyman L. Green, Marion, Va., assignors to Harwood Manufacturing Corporation, New York, N. Y., a corporation of New York

Application November 22, 1943, Serial No. 511,272

3 Claims. (Cl. 2—83)

This invention relates to garments and more particularly to bifurcated garments, for example, pajamas.

One object of the invention is to provide a bifurcated garment of such a construction as to enable the garment to be formed of a minimum number of parts and at the same time to be yieldably stretchable laterally in the portion thereof above the crotch and also vertically at the back of the garment in a direction extending between the crotch and the waistline.

Another object of the invention is to provide a pajama garment which may be formed entirely of inelastic woven fabric and which is yieldably stretchable at the waistline.

A further object of the invention is generally to provide an improved bifurcated nether garment, particularly in respect to the simplicity of its construction and its comfort in use.

The above and other objects, features and advantages of this invention will be fully understood from the following description, reference being had to the accompanying illustrative drawing.

In the drawing:

Figure 1 is a front view of a garment embodying the present invention;

Figure 2 is a view of the back of said garment; and

Figures 3, 4, and 5 are plan views of the parts of the garment before they are assembled and secured in garment-forming relation.

Referring now to the drawing in detail, the garment here shown as a pair of pajamas comprises two leg sections 12 formed of the parts illustrated in Figures 3 and 4, and a rear section 14 formed of the part illustrated in Figure 5, all of said sections being preferably formed of woven fabric. Each leg section 12 comprises a part which forms the leg portion of the garment and a portion of the garment above the crotch. Sections 12 are cut on the straight of the goods and are disposed in the garment on the straight of the goods, while section 14 is cut on the bias and is disposed in the garment on the bias. Said part 14 extends laterally of the garment between the adjacent edges of the upper portions of the two leg sections 12 and extends longitudinally of the garment from the waistline to the crotch.

The leg sections 12 are stitched together at the front of the garment at the central seam 16 which extends upwardly from the crotch to the fly of the garment, and the portions of the leg sections 12 above the crotch extend laterally

from seam 16 and the fly-forming portions thereof, respectively, toward the back of the garment and terminate with the edge portions 18 of said two leg sections in laterally spaced relations. Said edge portions 18 extend downwardly in converging relation from the waistline toward the crotch and are secured to the adjacent downwardly converging side edges 20 of part 14 by the seams 22 which extend downwardly from the waistline of the garment to the crotch. The lower edge 24 of part 14 is stitched to an upper portion of the edge 26 of the leg sections 12 by a seam 28 which, in the garment, is disposed along a line extending laterally between the leg portions of the garment at the crotch. In Figures 3 and 4, the part of edge 26 of leg section 12 which is stitched to a part of the lower edge 24 of part 14 is indicated as that part of the edge 26 of the leg section 12 which extends between the points A and B. Each leg portion of the garment is formed by stitching together the opposite side edges 26 and 30 of the companion leg section 12 by the seam 32 which extends from the point B of edge 26 to the bottom edge of the leg section and from the point C at the upper end of edge 30 of said leg section to the bottom edge thereof. The edge portion 32 of leg section 12 above said point C extends upwardly from the crotch at the front of the garment from a point mid-way of the seam 28, and lower portions of said edges 32 of the two leg sections are stitched together at the front of the garment to form the seam 16 below the fly. The parts of said edge portions above said seam are separable and are provided with buttons and button-holes or other separable fasteners in any suitable way. Upper edge portions of sections 12 and part 14 are folded and stitched as indicated at 34, to form a hem, or tube for the usual draw-string 36 by which the waist portion of the pajamas are adjustably secured around the waist of the wearer.

Thus it is seen that the garment constructed as described above, is well adapted to accomplish the several objects of the invention. Further, it will be noted that the part 14 which constitutes a rear panel of the garment above the crotch provides a desirable fullness in the seat portion of the garment, as illustrated by the fold indicated at 38 in Figure 2, and this together with the yieldable stretchability of said panel longitudinally and laterally of the garment prevents discomfort to the wearer at the crotch. Also, by reason of the yieldable stretchability of the panel or part 14, the part of the garment

above the crotch is yieldably stretchable circumferentially of the garment completely there-around. It is to be noted also that by reason of the yieldable stretchability of the upper folded edge portion of part 34 at the waistline of the garment the latter is yieldably stretchable completely around the garment at the waistline, and for this reason it is unnecessary to provide the garment with rubber or other elastic inserts at the waistline. Various other advantageous features of the garment constructed as described above will be apparent to those skilled in the art.

While we have shown and described a preferred embodiment of our invention, it will be understood that the invention may be embodied otherwise than as herein specifically illustrated or described, and that in the illustrated embodiment certain changes may be made and additions provided without departing from the underlying idea of this invention as defined by the scope of the patent claims.

Having thus described our invention and illustrated its use, what we claim as new and desire to secure by Letters Patent, is:

1. A garment of the character described comprising two leg sections extending downwardly from the waistline of the garment and forming the two leg portions, respectively, of the garment, the parts of said leg sections which extend from the crotch to the waistline having fly forming portions at the front of the garment and extending laterally from said fly-forming portions, respectively, toward the back of the garment and terminating in longitudinal edges spaced laterally from each other, and a rear panel extending downwardly from the waistline of the garment to the crotch thereof, said rear panel being formed of woven fabric and disposed on the bias in the garment, said rear panel having longitudinal side edges stitched to the adjacent longitudinal edges, respectively of said leg sections and having a bottom edge portion stitched to adjacent edge portions of said leg sections, respectively, along a line extending laterally between said leg portions at the crotch of the garment, said rear panel extending from the crotch to the waistline of the garment and forming a substantial part of the waistline of the garment whereby the latter is resiliently stretchable and contractable at the waistline circumferentially of the garment.

2. A garment of the character described comprising two leg sections each formed in one piece and extending from the waistline to the lower end of the companion leg portion of the garment,

5 each of said leg sections having longitudinal side edges which are stitched together for a part of the length of the leg section to form a leg portion of the garment, and a rear panel extending from the waistline of the garment downwardly to the crotch of the garment, said rear panel being formed of woven fabric and disposed on the bias in the garment, said rear panel having opposite side edges stitched to adjacent side edge portions of said leg sections, respectively along lines extending downwardly in converging relation from the waistline to the crotch and a lower edge portion stitched to adjacent edge portions of said leg sections at the crotch along a line 10 extending laterally between the leg portions, said 15 rear panel extending from the crotch to the waistline of the garment and extending at its upper part substantially the full width of the back of the garment at the waistline of the garment whereby the latter is resiliently stretchable and contractable at the waistline circumferentially of the garment.

3. A garment of the character described comprising two leg sections extending downwardly from the waistline of the garment and forming the two leg portions, respectively, of the garment, the parts of said leg sections above the crotch extending laterally of the front of the garment toward the rear thereof and terminating in longitudinal edges spaced from each other laterally of the garment and extending downwardly from the waistline to the crotch along downwardly converging lines, and a rear panel disposed on the bias in the garment and having downwardly 25 converging side edges extending from the waistline to the crotch and stitched to the adjacent longitudinal edges, respectively, of said leg sections, said panel having a bottom edge extending 30 between the lower ends of said converging side edges thereof and stitched to adjacent edge portions of said leg sections along a line extending laterally of the garment in the region of the crotch, said rear panel extending from the crotch to the waistline of the garment and extending at its upper part substantially the full width of the back of the garment at the waistline of the garment whereby the latter is resiliently stretchable and contractable at the waistline circumferentially of the garment, said garment having a fly, and said leg sections being 35 stitched together at adjacent edge portions thereof along a line extending from the crotch to the lower end of said fly.
